Attorney

UNITED STATES PATENT OFFICE.

CHARLES A. BALLREICH, OF LOS ANGELES, CALIFORNIA.

SYRINGE.

Application filed December 15, 1926. Serial No. 154,871.

This invention has to do generally with syringes and is more particularly concerned with syringes used for flushing or irrigating the vagina.

5 It is known that the defining walls of the vagina are normally more or less flabby and tend to cling together in a manner to resist thorough flushing and cleansing between the folds. I have provided a syringe having a 10 dilator which is adapted to dilate the vagina walls in a manner to open out the folds and thus give full access to the flushing stream, to the end that the cleansing operation may be thorough and effective.

15 Now I am aware that heretofore there have been syringes provided with devices intended to perform this function, but their common fault seems to have been that they have been so "harsh" that the pain accompanying their 20 application has led to discontinuance of their use. Furthermore, these devices, while having a distending effect on the vagina, as a whole, have usually been of a nature to compress the wall-folds together in an entrapping 25 manner, rather than separating said folds.

Another short-coming has been their comparative bulk and complication, both of which characteristics are most undesirable, 30 as will be readily understood. The above statements are not made in the spirit of derogation, but merely that my advance in the art may be more clearly pointed out.

I have provided a dilator having characteristics which not only insure proper distension of the vagina and opening out of the wall-folds but also enable the entry, use and withdrawal of the syringe without causing pain, to the end that the use of the syringe is 40 encouraged and harmful results avoided.

Generally, I accomplish this by the provision of a dilator held to the syringe stem near its nozzle end, the dilator comprising a body portion about the stem and from which 45 project radial, flexible arms of a length and degree of rigidity sufficient to extend and hold out the walls of the vagina so access is had to the complete surface thereof. However, the arms have sufficient inherent flexibility to allow them to yield and bend substantially parallel to the stem as the syringe is inserted or withdrawn through the orifice, to obvious advantage. The resiliency of the arms is such that they assume an extended 50 position as soon as they clear the orifice.

The dilator may be considered as of star

formation, the points being adapted to engage the vagina walls at spaced points, thereby insuring a proper extension and yet not overlying too much surface nor preventing the free flow of fluid from the syringe.

Preferably, though not necessarily, I also provide the syringe stem with a distender adapted to act on the orifice walls during use of the syringe. While this distender is used 65 to advantage in combination with the dilator above described, it is also useful in connection with syringes having no dilator or having a dilator different to that disclosed. Therefore, the combination of the stem and distender, without the inclusion of the dilator, is made the subject matter of certain of my claims.

This distender is preferably in the nature of a fluted sleeve, preferably somewhat pear-shaped, the ribs of the sleeve being adapted to engage the orifice walls to prevent them from closing down on the syringe stem, proper, and the channels between ribs providing a passageway for the outlet of flushing fluid. While the distender may be a sleeve of rubber adapted to be slipped over the stem, my broader claims contemplate the substitution of an integral enlargement of the stem, said enlargement serving as a distender 80 and being grooved longitudinally to provide the desirable passageways.

Other objects and novel features of the invention will be made apparent in the following detailed description, reference being had 90 to the accompanying drawings, in which—

Fig. 1 is an elevation of the preferred embodiment of my invention;

Fig. 2 is a top plan view of Fig. 1, the showing of the distender being omitted;

Fig. 3 is a section on line 3—3 of Fig. 1;

Fig. 4 is a section on line 4—4 of Fig. 1; and

Fig. 5 illustrates a variational manner of applying the distender to the syringe stem.

In the drawings I have shown a syringe embodying a tubular stem 10 which preferably tapers from its rounded and apertured nozzle end 11 to the fluid inlet end 12. A hose 13 is applied to end 12 in the usual manner and leads from a relatively large capacity fluid-reservoir 14. There may be a usual force-bulb 15 in the hose line in order to create forcible jets through the nozzle apertures 16 which open from stem bore 17.

My dilator is indicated generally at 18 and is characterized as a star-shaped member

made up of ring-like body portion 19 and normally radially extending points or arms 20, these arms being smoothly rounded throughout. Arms 20 are made of a yieldable, resilient material such as rubber and may be integral with body portion 19, the degree of rigidity of the arms (tending to hold them normally projected in the manner shown in Fig. 1) is sufficient to hold the relatively yielding walls of the vagina extended and to open out the wall-folds, but the arms are sufficiently flexible to permit them being bent either backwardly or forwardly, as shown in dotted lines in Fig. 4, into substantially parallel relation with the stem during insertion and withdrawal, respectively, of the syringe. The yieldability is such that this bending may be accomplished without fear, injury or pain to the user.

As described at the forepart of this description, the dilator arms spread the vagina walls in a manner to expose them fully to the action of the spray from nozzle 11, and this insures a thorough cleansing. In view of the somewhat full remarks previously made in this connection, this point will not be enlarged upon here.

While the arms 20 may be held to the stem in any suitable manner, I preferably provide an annular groove 21 in the stem near nozzle 11, the body member 19 being first radially expanded as it is slipped along the stem into registry with the groove and then, by virtue of its inherent resiliency contracting into said groove, being thereby positioned on the stem.

I have provided a distender 22 on stem 10, said distender preferably being in spaced relation with respect to extender 18. While this dilator may be characterized as an enlargement of and therefore integral with the stem (and my claims contemplate such a characterization) preferably it is in the form of a separate rubber sleeve slipped over the small end of the stem and held in any suitable manner, as by friction, in proper position on the stem. In such a case, and as illustrated in Fig. 5, the dilator may be adjusted longitudinally along the stem to suit the individual requirements. Or it may be contracted into an annular recess 23, as in Fig. 4, to hold it more or less fixedly in a given position.

Dilator 22 is preferably somewhat pear-shaped, the smaller, rounded end facing extender 19, and it is fluted to provide surface depressions or waterways 24 which preferably extend substantially parallel to the axis of the stem. The ribs 25 which define these passageways are adapted to spread or distend the walls of the vagina orifice, thus

holding said walls clear of passageways 24 and insuring the free outward flow of flushing fluid, a very important provision, as will be understood.

It will be noted that the syringe is of a most simple nature, requires no special attention to prepare it for immediate use, and, due to its nature and appearance, relieves prospective users from any fear of its employment, its use hence being encouraged.

It will be understood the drawings and description are to be considered merely as illustrative of and not restrictive on the broader claims appended hereto, for various changes in design, structure and arrangement may be made without departing from the spirit and scope of said claims.

I claim:

1. In a device of the character described, a relatively rigid tubular stem having nozzle apertures near one end thereof, the stem being provided with an annular groove at a point adjacent the apertures, and a dilator on the stem, said dilator being characterized as a ring-like body portion having radial, resilient arms formed of soft yielding material, said body portion being radially sprung into the groove and thereby positioning the dilator longitudinally on the stem.

2. In a syringe, a relatively rigid tubular stem having nozzle apertures near one end thereof, and a dilator surrounding said stem having a ring portion adjacent said apertures, a single row of flexible arms formed of relatively soft elastic material extending outwardly from said ring at right angles to said stem, said arms being yieldingly connected to said ring portion whereby they may be bent from the position at right angles to the stem to a position parallel to the stem.

3. In a syringe, a tubular stem formed of relatively rigid material and having a nozzle end, an independent dilator of relatively soft material on said stem and having a plurality of spaced fingers adjacent said nozzle end and adapted to dilate the walls of the cavity into which the syringe is inserted, and a distender on the stem spaced from the dilator and adapted to distend the opening into the cavity, said distender comprising a plurality of arms extending longitudinally of the stem and providing passageways therebetween, said dilator fingers and said distender arms being formed of soft yielding material whereby they may be bent around the stem.

In witness that I claim the foregoing I have hereunto subscribed my name this first day of December 1926.

CHARLES A. BALLREICH.
